UNITED STATES PATENT OFFICE.

WILLIAM H. THORNLEY, OF READING, PENNSYLVANIA.

FIRE-BOX FOR STEAM-BOILERS.

SPECIFICATION forming part of Letters Patent No. 769,417, dated September 6, 1904.

Application filed June 26, 1899. Renewed December 20, 1902. Serial No. 136,087. (No model.)

To all whom it may concern:

Be it known that I, WILLIAM H. THORNLEY, a citizen of the United States, residing at Reading, in the county of Berks and State of Pennsylvania, have invented certain new and useful Improvements in Fire-Boxes for Steam-Boilers; and I do hereby declare the following to be a full, clear, and exact description of the invention, such as will enable others skilled in the art to which it appertains to make and use the same.

My invention is an improvement in fire-boxes for steam-boilers; and it consists in the novel construction and arrangement of its parts, as hereinafter described.

The object of my invention is to construct a fire-box adapted especially to be used in combination with one or more hydrocarbon-burners, said fire-box being so constructed as to become rapidly heated and retain the heat for a considerable length of time after the burners have been turned off. The box is also so constructed as to distribute the heat to the best advantage.

In the accompanying drawings, Figure 1 is a longitudinal sectional view showing a fire-box in proper relation to the boiler, and Fig. 2 is a transverse sectional view cut on the line 22, Fig. 1.

The boiler 1 is of ordinary construction and is set in the brickwork in the ordinary manner, the bridge-wall 2 having a space 3 of about one inch between its upper end and the boiler. In the fire-box the grates 4 are covered with the brick bed 5. The brick bed or partition provides means for separating the pit 5^a from the combustion-chamber 5^b. The hydrocarbon-burners 6 are passed through the front wall of the fire-box, and said burners may be of any construction, or they are preferably constructed as shown in my application, Serial No. 136,804, filed in the Patent Office December 27, 1902. About five inches from the front wall is located the vertical low deflector-wall 7, said wall projecting above the level of the said burners and extending the entire width of the fire-box, or the said deflector-wall instead of extending the entire width of the fire-box may be made in sections. Immediately behind the deflector-wall, between the

latter and the bridge-wall, is located a number of vertical honeycombed walls 8, having spaces 8^a of about one inch between their upper ends and the boiler. The honeycombed walls are made of brick with broken joints 55 made by leaving out each alternate brick in the tier. The honeycombed walls are about eight inches apart, and the openings in the one wall are opposite the brick in the next wall, so that the heat in passing through the 60 honeycombed walls must proceed in a tortuous route.

In operation the hydrocarbon-burners 6 are lighted, and the flame is thrown against the deflector-wall 7. The heat passes over the 65 said wall and passes through the openings in the honeycombed walls and almost instantaneously makes the brick of the said honeycombed walls white hot. The heat then passes over the bridge-wall, around the boiler, 70 through its tubes, and out of the brickwork through the openings 9. The heat is retained for a considerable length of time by the honeycombed walls after the burners are shut off and is evenly distributed about the boiler. 75 After the burners 6 have been shut off the heat from the honeycombed walls 8 will retain the steam in the boilers for about a half hour or longer.

Having described my invention, what I claim as new, and desire to secure by Letters Patent, is—

1. A fire-box comprising a front wall, a bridge-wall, a pit, a combustion-chamber, a bed, located between the front wall and the 85 bridge-wall, and separating the pit from the combustion-chamber, a low deflector-wall located on the bed, a series of honeycombed walls located on the bed between the deflector-wall and the bridge-wall, and means for directing a flame against the deflector-wall.

2. A fire-box comprising a front wall, a bridge-wall, a bed located between the front wall and the bridge-wall, a low deflector-wall located on the bed, a series of honeycombed 95 walls, located on the bed between the deflector-wall and the bridge-wall, and having the openings in one wall located opposite to the solid part of the next wall, and means for directing a flame against the deflector-wall.

3. A fire-box comprising a front wall, a bridge-wall extending upward so as to leave a narrow space between the bridge-wall and the boiler-space, a bed located between the 5 front wall and the bridge-wall, a low deflector-wall located on the bed, a series of honey-combed walls of approximately the same height as the bridge-wall and located on the bed between the deflector-wall and the bridge-

wall and means for directing a flame against 10 the deflector-wall.

In testimony whereof I affix my signature in presence of two witnesses.

WILLIAM H. THORNLEY.
